UNITED STATES PATENT OFFICE.

THORVALD C. COLBIORNSEN, OF ANTONITO, COLORADO.

AUTOMATICALLY ACTUATED BRUSH FOR GRAINER PIPES.

Application filed September 7, 1927. Serial No. 218,069.

This invention relates to the art of salt making, and particularly to means for keeping the parallel steam coils of salt grainers free from incrustations or scale deposits.

5 The general object of the invention is to provide for this purpose brushes operating over the grainer pipes and reciprocated along the pipes automatically by power, thus doing away with the necessity of brushing these 10 grainer pipes by hand as is the case today.

A further object is to provide means whereby the brushes may be reciprocated over a certain portion of a grainer pipe, then advanced, and again reciprocated over a certain other 15 portion of the grainer pipe, and so on backward and forward across the grainer pipes so as to keep their entire length free from incrustations or deposits.

A still further object is to provide means 20 for this purpose which includes a constantly operated power driven shaft, a constantly reciprocated rack bar, a carriage which supports the brushes, and means for intermittently connecting the carriage to the rack 25 bar to cause the rack bar to reciprocate the carriage for a certain relatively short distance and then disconnect the carriage from the rack bar and upon a rearward or forward movement of the rack bar again connect the 30 carriage thereto to thus cause the reciprocation of the carriage and a step by step forward or rearward movement of the carriage along the steam coil.

Other objects will appear in the course of 35 the following description.

My invention is illustrated in the accompanying drawings, wherein:

Figure 1 is a top plan view of a portion of 40 a grainer with the grainer pipes and my brushing apparatus applied thereto;

Figure 2 is a section on the line 2-2 of 45 Figure 1;

Figure 3 is a section on the line 3-3 of 50 Figure 1;

Figure 4 is a fragmentary section through 55 the grainer tank showing the means for supporting the carriage, the angle irons of the carriage being in section;

Figure 5 is a fragmentary top plan view 60 enlarged and partly in section of the driving shaft, the clutches, the crank and a portion of the carriage, the rack bar being shown in section;

Figure 6 is a fragmentary side elevation of

a portion of the construction shown in Figure 5, the support for the cam shaft and the wall of the grainer tank being in section;

Figure 7 is a vertical section of a portion of the carriage and one of the steam pipes, the vertical standard of the carriage being in section;

Figure 8 is a top plan view of the brush mounting and brush;

Figure 9 is a section on the line 9-9 of Figure 7;

Figure 10 is a top plan view of the lock enclosing column;

Figure 11 is a section on the line 11-11 of Figure 9;

Figure 12 is a section on the line 12-12 of Figure 9;

Figure 13 is a perspective view of the clutch reversing lever;

Figure 14 is a perspective view of the yoke.

Referring particularly to Figures 1, 2 and 75 3, A designates a grainer or pan which is, of course, of the usual construction and may be formed in any suitable manner. Extending longitudinally through this grainer are a plurality of steam pipes B, these pipes being 80 all connected to a header C in the usual manner, this header being located outside of the end wall D of the grainer. The steam pipe E carries the steam away from each pipe B. The pipes B are supported by means of hangers F of any suitable character from transverse beams G. So far I have described what is commonly found in grainers.

The side walls of the grainer carry upon them the angle iron tracks 10 and mounted 90 upon these tracks is a carriage which includes the transversely extending angle irons 11 which are connected at their ends by the upright brackets 12, in turn connected to longitudinally extending angle irons 13 carrying wheels 14 which operate upon these tracks.

The carriage carries upon it a plurality of sets of brushes, as will be later described, which engage the grainer pipes B, as shown in Figure 2, so as to sweep the incrustation from 95 these pipes. At the middle of the carriage there is disposed an upright column 15, shown in detail in Figures 9 to 12 and in Figure 7. The upper end of this column is formed with a vertical notch 16, and coacting with the upper end of this column is a rack bar 17 which, as shown in Figure 7, is T-shaped in cross section. This rack bar is formed with

notches 18 extending upward from the lower edge of its vertical web.

Disposed within the column is a bolt or latch 19 which slides vertically within the column and carries a stem 20. This stem extends downward through the column 16 and is urged upward by means of a compression spring 21 bearing against a shoulder 22 on the stem 20 and at its lower end bearing against any suitable abutment 23. Thus this latch 19 or bolt is urged upward and into engagement with the lower edge of the rack bar 17 or into engagement with the notches therein. The bolt 19 is formed on its edge face with an inwardly extending slot 24 whose purpose will be later stated.

Referring now to Figures 1, 3 and 5, it will be noted that there is provided outward of the end wall and above the level of the end wall of the grainer a transversely extending driving shaft 25, which at the middle of the grainer is formed with a crank 26. This driving shaft carries upon it the six-inch beveled gear wheel 27. The crank 26, as shown in Figure 1, is connected by a connecting rod 28 to the rack bar 17 and thus this rack bar is constantly reciprocated. The rack bar is supported, as shown in Figure 7, in guides operatively mounted upon the transverse beams G. As shown in Figure 7, this mounting comprises a saddle 29 having an outwardly projecting lug 30, this saddle 29 having formed therewith the angular members 31 (see Figure 3) which support the hangers F by means of the supporting bolts 32. The saddle 29 has a portion extending downward, as shown in Figure 3, which portion carries at its upper end the lug 30.

Bolted to the lower end of the depending portion of the saddle 29 is an angular hanger 33 and this hanger, as shown in Figure 7, has bolted to it the lower plates 34 which are recessed so as to extend beneath and form a guide for the rack bar 17. Thus the rack bar 17 is guided in these hanger members 34 and has free reciprocating movement therein, there being as many of these hangers as there are transverse beams G. Of course, it will be understood that in Figure 3 the figure is cut across so as to shorten it and only two beams are shown but that any number of transverse beams may be provided, depending upon the length of the grainer.

Mounted in bearings at right angles to the shaft 25 is a longitudinally extending shaft 35 which is disposed to one side of the rack 17 and slightly lower than the rack shown in Figure 7. This shaft is preferably tubular and is mounted in bearing brackets 36 forming part of the hangers 33. This shaft carries mounted loosely upon it the combined gear wheel 37 and clutch member 38, which will be hereafter termed the gear wheel clutch member. As before remarked, this clutch member is loose upon the shaft and is held in

position with the gear wheel 37 engaging the gear wheel 27 by means of the collar 39 which is pinned upon the shaft.

It will be seen from Figure 5 that the gear 37 is twice as large as the gear wheel 27, the gear wheel 27 in actual practice being six inches in diameter, while the gear wheel 37 will be twelve inches in diameter. Slidably mounted upon the shaft 35 but rotating with this shaft is a clutch member 40. This is mounted upon the shaft 35 by means of the transverse pin 41 extending through a slot 42 in the shaft (see Figure 5) and is urged toward the clutch member 38 by means of the compression spring 43, which at one end bears against a fixed abutment 44 and at the other end bears against the clutch member 40, which will be hereafter termed the cam clutch member. A shipper ring 45 engages this clutch member 40 so as to shift it into or out of engagement with clutch member 38. When in engagement with the clutch member 38, it is obvious that the shaft 35 will be rotated by the shaft 25 and that when the clutch members are shifted outward or apart, the shaft 35 will be idle. The clutch member 40 is shifted into or out of engagement with the clutch member 38 automatically, as will be later described.

As shown in Figure 6, the shaft is mounted in bearing brackets 46 or other suitable bearings carried upon the wall of the grainer and the shaft is held from any reciprocation by the collars 47, one of which constitutes the abutment against which the spring 43 bears. The ring 45 has the rods 48 extending longitudinally from it above and below the shaft. It is to be noted from Figure 6 that the clutch members 38 and 40 are provided with four teeth disposed in quartering relation so that the clutch members may make a quarter turn before engaging with each other, as will be later stated.

The cam shaft 35 carries upon it the outwardly projecting, longitudinally extending cam or fin 49 which engages a tappet 50 projecting outward from a collar 51 surrounding or mounted upon a short shaft 52 carried upon a bracket 53 projecting from the upper end of the column 23 (see Figure 7). This collar 57 carries upon it the inwardly projecting arm 58 which extends through an opening 59 in the column and engages the lower wall of the slot 24. This slot 24, as shown in Figure 7, extends inward, then downward, then upward as regards its lower wall, and then outward so that the lower wall is tapering and the arm 58 rests upon the upper end of this tapered portion constituting the lower wall of the slot 24. When the cam 49, moving in a clockwise direction, strikes the arm 50, it will depress the arm 58, which will depress the latch, thus disconnecting the carriage from the reciprocating rack bar, and when the cam has passed the arm 50 the

spring 21 will force the lock back into its engagement with the rack bar. At the point where the bracket 36 extends downward, it is necessary to provide an outwardly bowed link

5 60 to extend around the cam shaft 35, but otherwise than this the links of the hangers F are of any ordinary or suitable type.

The rods 48 which are connected to the clutch member 40 engage a pivoted lever or 10 yoke, shown in Figure 14. This yoke is designated 61 and is provided with two spaced arms 62 bifurcated for the reception of the rods 48. The yoke is pivoted upon a pivot pin 63 to a bracket 64 extending from the 15 wall D of the grainer and this yoke is provided with the outwardly projecting tongue 65, through which the pivot pin 63 passes, having a tooth 66. This tooth is adapted to engage in or against a flange 67 of the flanged- 20 column 15 (see Figure 12) when the carriage moves rearward to what may be termed its initial position. At the opposite end of the path of travel of the carriage, there is mounted upon the beam G (see Figure 3) the 25 shipper lever 68 illustrated in Figure 13. This lever is mounted upon a bracket 69 and is formed with a lug 70 through which a connecting rod 71 passes, which connecting rod 30 engages with the upper arm of the yoke or lever 61 and is formed with the laterally projecting arm 72 which projects into the path of movement of the column 15. It follows, therefore, that when the column, which is part of the carriage, has moved to the left in 35 Figure 3 to the end of the grainer remote from the driving shaft 25 that the carriage will strike this shipper lever 68 and through the connecting rod 71 and the rods 48 will shift the clutch member 40 out of engagement 40 with the clutch member 38. The same result will happen when the carriage is returned to its initial position by the column striking the toothed extremity of the lever 61, thus pulling upon the rods 48 to withdraw clutch member 45 40 from engagement with the clutch member 38. The specific operation of this mechanism will be presently described.

The brushes are shown in Figures 7 and 8. Mounted upon the pair of angle irons 11 50 are the upwardly extending standards 73, each of these standards being formed with an inwardly projecting lug 74. Two oppositely disposed pairs of brushes are used, these brushes being mounted upon arcuate bags 75 55 and having wire or other bristles 76 extending inward and in contact with the steam pipes B. These bags 75 are mounted upon the upwardly extending shanks 77 which carry the downwardly opening hooks 78. 60 These engage over the transverse bolts 79 which extend between the lugs 74 of the standards 73 on that side. The shanks 77 extend upward beyond these hooks 78 and are bolted by bolts 80 to the longitudinally extending connecting webs 81 which connect the

upper ends of the standards 73 on that side. The hooks 78 make it easy, upon the removal of the bolts 80, to lift up upon the brushes and displace them from their engagement with the pipe B.

The vertical limb or web of the rack 16 is provided with notches 82 previously referred to, these notches having a length of approximately four inches and the distance from the center of one notch to the next adjacent notch being 2' 6". The throw of the crank 26 will be three feet and the reciprocations transmitted to the rack bar will be three feet. The coupling clutches, as previously described, are laid out radially and in quadrants, that is four in all. Therefore, if the cam shaft clutch member 40 is unclutched momentarily, the cam shaft 35 will remain stationary until the gear clutch 38 has made a one-quarter revolution. Then 85 the clutches will again be in contact, or in other words the crank shaft will make one-half revolution and the rack bar 17 one reciprocation from the time the cam shaft clutch member 40 is momentarily acted upon 90 and the cam 49 is stopped until it starts up again. The function of the cam 49 is to stop the car momentarily by coming in operative engagement with the locking bolt 19 and pulling the bolt out of the notch on the 95 rack bar. As the rack bar 17 is in constant reciprocation, the notch on the same in which the lock was engaged will have passed out of line with the lock and the car will, therefore, remain stationary until another notch either 100 to right or to left on the moving rack 17 gets in line with the lock.

The relative motion of the parts is as follows: One revolution of the crank shaft 25 equals two strokes of the rack bar 17, one 105 revolution of the crank shaft 25 equals one-half revolution of the cam shaft 35 and, therefore, two strokes of the rack 17 equals one-half revolution of the cam shaft or one stroke of the rack will equal one-quarter revolution 110 of the cam shaft. These relative ratios are necessary to be remembered when considering the operation of the mechanism. Assuming that the brushing car and the rack bar 17 are locked together at the end of one 115 reciprocation or stroke, for instance to the right of the observer in Figure 3, then the car will make three reciprocations with the rack bar and at the end of the fourth reciprocation will be in a position beneath the first beam on the right in Figure 3.

The pinion 27 on the crank shaft is keyed in such position that when the clutches are engaged and three strokes have been made, then on the fourth stroke the cam 49 starts 125 immediately to operate on the lock lever 50 to shift the lock downward clear of the notch 82 in the rack bar. As the angular motion of the cam 49 is one-half that of the crank for a given time, the rack bar 17 will 130

have started on its stroke to the left before the lock is liberated from the cam 49. In consequence of this, the car supporting the brushes remains stationary. When the next 5 notch in the rack bar moving to the left, therefore, comes in line with the lock of the stationary car, the lock drops into the notch and the car will go with the rack bar to the end of the stroke toward the left. The 10 crank shaft has now made a one-half revolution, the rack bar 17 one stroke from right to left, and the cam a one-quarter revolution. At the end of the following stroke, which is to the right, the cam has made an 15 other one-quarter revolution and at the end of the next stroke to the left the cam has moved another quarter of a revolution and at the end of the fourth stroke or to the right another quarter of a revolution, or in all the 20 cam has made one revolution.

The relative positions of the parts are now identical to the position originally stated, namely the rack bar is at the end of the oscillation to the right and the cam is again 25 ready to act on the lock lever. The car will, therefore, engage the next notch to the right as rack bar makes a stroke to the left. The car is therefore, advanced two notches to the left or approximately five feet. As the 30 motion of the car is slower at each end of the operation and nothing at all at one moment and most rapid at the middle of the operation, the distance between the centers of the notches is 2' 6" or half the length of 35 the stroke. Therefore, all parts of the piping will receive an equal service in regard to the speed of the brushes. At the end of the last stroke or reciprocation at each end of the grainer the car bracket or column 15 40 will come in contact with the lever 68 or lever 61 and draw the cam clutch out of engagement with the gear clutching member. The car acts on each clutch lever twice, after which the travel of the car or carriage is 45 reversed. Should it be desired to stop the carriage at any time, the yoke end of the connecting rod 71 may be lifted from its engagement with the yoke 61 and suspended temporarily. In case of reversal of the travel, a momentary pull on the hand lever (not shown) which may be connected to the shipper ring 45 will change the relative position 50 of the cam and rack bar and, therefore, reverse the car travel.

55 Attention is particularly called to the pipe hanger shown in Figure 7, inasmuch as these pipe hangers permit of continuous and unobstructed treatment by brushing every part of the pipe. Ordinarily for the suspension 60 of grainer pipes as well as for piping in general, the ordinary round iron staple hanger is used having two vertical members, one on each side of the pipe and forming the semi-circular saddle under the same, the members 65 being anchored to cross beams above the

grainer. An attempt to make a pair of semi-circular brushes pass an obstruction presented by a four-inch staple or straddle hanger would result in immediate obstruction and breaking up of the wire in the brushes 70 unless the brushes were automatically forced to open or spread apart in passing the hangers, in which case nearly 15% of the piping would be excluded from contact with the brushes and the brushing arrangement would, 75 therefore, fall far short of its necessary function.

As shown in Figure 7, the pipe hanger consists of the band F which is $\frac{1}{8}$ " by $\frac{3}{4}$ " wide and to this band is riveted a circular band of the same dimensions which embraces the pipe. This is welded or riveted to the vertical portion F. This in turn is supported from the beams G in the manner shown in the drawings. The brush hangers 77 are made of 80 spring band steel so that they are flexible and permits the brushes to yield as they pass these hangers, or rather as the bristles pass the pipe-embracing portion of the hangers. 85

I claim:

1. The combination with a pipe, of a cleaning means mounted upon the pipe and operating thereon, means for causing the cleaning means to reciprocate longitudinally of the pipe, the length of the reciprocation being 90 relatively short and means to intermittently advance the cleaning means step by step along the pipe with respect to said reciprocating means for the full length of the pipe. 95

2. The combination with a plurality of 100 pipes, of brushes mounted upon each pipe and operating thereon, power operated means for causing the brushes to reciprocate longitudinally of the pipe, the length of stroke of the brushes being relatively short, and means 105 for intermittently advancing the brushes step by step along the pipes for the full length thereof.

3. The combination with a plurality of 110 pipes, of brushes mounted upon each pipe and operating thereon, power operated means for causing the brushes to reciprocate longitudinally of the pipes, the length of stroke of the brushes being relatively short, and means for 115 intermittently advancing the brushes step by step along the pipes for the full length thereof and automatically reversing the movement of the brushes at each end of their journey along the pipe.

4. The combination with a pipe, of a cleaning device mounted upon the pipe and operating thereon, means for shifting the cleaning means longitudinally along the pipe from end to end thereof and giving the cleaning means reciprocations having an amplitude relatively 120 short with relation to the pipe and including a constantly operated reciprocating member, means for operatively connecting the cleaning means to said reciprocating member for movement therewith and intermittently re- 125 130

- leaving the connection between the cleaning means and the reciprocating member whereby to permit the reciprocating member to move forward or backward with relation to the cleaning means during this period of disconnection to thus cause a step by step advance of the cleaning member along the pipe.
5. The combination with pipes extending parallel to each other, of brushes mounted upon the several pipes for engagement therewith, a carriage operatively supported for movement parallel to the pipes for the full length thereof, and power operated means for causing the carriage to travel from one end 15 of the pipes to the other and back again and simultaneously restricting the brushes through strokes of amplitude relatively small with relation to the length of the pipes.
6. The combination with parallel pipes, 20 of brushes mounted upon the several pipes for engagement therewith, means for giving a reciprocation to the brushes of relatively short amplitude compared with the length of the pipes, and intermittently advancing the 25 brushes step by step along the pipes to thereby cause the brushes to operate over the entire length of the pipes.
7. The combination with parallel pipes, 30 and hangers supporting said pipes, of brushes disposed upon and operating on the several pipes, a carriage mounted for movement longitudinally of the pipes, means for causing the carriage to travel longitudinally of the pipes for approximately the full length 35 of the pipes, and means for causing reciprocation of the brushes relative to the carriage, the reciprocations having amplitudes less than the length of the pipes.
8. The combination with parallel pipes, 40 and hangers supporting the pipes, of brushes disposed upon and operating on the several pipes, a carriage movable longitudinally of the pipes, means for supporting the brushes, and power operated means for moving the carriage longitudinally of the pipes from one end to the other of the pipes and simultaneously giving the carriage reciprocations of short amplitude relative to the length of the pipes.
50. 9. The combination with a pipe, of a brush mounted upon the pipe for movement therewith, power operated means for moving the brush along the pipe including a rack bar extending longitudinally of the pipe, power operated means for constantly reciprocating the rack bar, means for interlocking the brush with the bar for reciprocation therewith during a plurality of strokes of the bar and intermittently disconnecting the brush from its 55 engagement with the bar to permit the bar to move forward or backward with relation to the brushes to thus cause a step by step advance of the brush along the pipe.
60. 10. The combination with parallel pipes, of 65 brushes disposed to surround the several pipes, a carriage movable longitudinally of the pipes, overhead transverse beams supporting the pipes, a longitudinally reciprocatable rack bar slidingly mounted upon said beams and extending longitudinally of the pipes, power operated means for constantly reciprocating said rack bar, an element mounted upon said carriage and moving therewith and having a slot through which the rack bar passes, a bolt disposed in the element and yieldingly urged against the rack bar and into the notches thereof, a longitudinally extending shaft, and means mounted upon and rotating with said shaft for intermittently engaging said bolt to retract it from the rack bar whereby to permit the rack bar to reciprocate through a stroke without reciprocating the carriage whereby to cause the travel of the carriage step by step from one end of the pipes to the other.
11. The combination with parallel pipes, of brushes disposed to surround the several pipes, a carriage extending below the pipes and movable longitudinally thereof, transverse beams supporting the steam pipes, a longitudinally reciprocatable rack bar slidingly mounted upon said beams and extending longitudinally of the pipes, power operated means for constantly reciprocating said rack bar, an element mounted upon said carriage and moving therewith and having a slot through which the rack bar passes, a bolt disposed in the element and yieldingly urged against the rack bar and into the notches thereof, a longitudinally extending shaft, means mounted upon and rotating with said shaft for intermittently engaging said bolt to retract it from the rack bar whereby to permit the rack bar to reciprocate through a stroke without reciprocating the carriage whereby to cause the travel of the carriage step by step from one end of the pipes to the other.
12. The combination with parallel pipes, of means for cleaning the pipes comprising brushes mounted upon the several pipes, a carriage movable parallel to the pipes and supporting the several brushes, means for causing a movement of the carriage from one end of the pipes to the other and back again and simultaneously reciprocating the carriage in strokes of relatively small amplitude comprising a power operated shaft having a crank, a bar operatively connected to the crank to be reciprocated thereby longitudinally of the pipes and having notches in its face, a member mounted upon the carriage and extending upward to said bar and having a slot in which the bar is disposed, a bolt mounted upon said member, a spring urging the bolt into engagement with the bar and the

- notches whereby the member and the carriage shall travel with said reciprocating bar, means for intermittently withdrawing the bolt from its engagement with the rack bar
- 5 comprising a longitudinally extending shaft, a trip cam mounted upon the shaft and adapted to operatively engage the bolt to momentarily retract it once upon each rotation of the shaft, means for causing a rotation of the longitudinal shaft at a less speed than the crank shaft, and means for momentarily disconnecting the longitudinal shaft from the crank shaft at each end of the travel of said carriage, said means being automatically actuated by the arrival of the carriage at the end of its travel.
- 10 13. The combination with parallel pipes, of means for cleaning the pipes comprising brushes mounted upon the several pipes, a carriage movable parallel to the pipes and supporting the several brushes, means for causing a movement of the carriage from one end of the pipes to the other and back again and simultaneously reciprocating the carriage in strokes of relatively small amplitude comprising a power operated shaft having a crank, a bar operatively connected to the crank to be reciprocated thereby longitudinally of the pipes and having notches in its face, a member mounted upon the carriage and extending upward to said bar and having a slot in which the bar is disposed, a bolt mounted upon said member, a spring urging the bolt into engagement with the bar and the notches whereby the member and the carriage shall travel with said reciprocating bar, means for intermittently withdrawing the bolt from its engagement with the rack bar comprising a longitudinally extending shaft, means for driving the longitudinally extending shaft from the crank shaft including coacting clutch members yieldingly urged into engagement with each other, a trip cam mounted upon the shaft and adapted to operatively engage the bolt to momentarily retract it once upon each rotation of the shaft, means for causing a rotation of the longitudinal shaft at a less speed than the crank shaft, means for momentarily disconnecting the longitudinal shaft from the crank shaft at each end of the travel of said carriage, said means being automatically actuated by the arrival of the carriage at the end of its travel, said means including levers operatively supported at the opposite ends of the travel of said carriage, and connecting means between said levers and the clutch members acting to cause disconnection between the clutch members when said levers are struck by the carriage.
- 15 14. The combination with a plurality of parallel steam pipes, and overhead transversely extending beams having hangers supporting the steam pipes, of means for cleaning the pipes comprising a longitudinally extending T-shaped rack bar mounted in guides operatively supported upon said beams, the depending web of the bar being provided with notches at intervals, a power driven crank shaft having a crank operatively connected to the bar to constantly reciprocate the bar, a carriage extending beneath the series of pipes and upward and operatively supported for movement longitudinally of the pipes at each end, a plurality of pipe brushes mounted upon said carriage, each for engagement with a pipe, a column extending upward from the carriage and having a slot receiving the depending web of the bar, a bolt mounted within the column and resiliently urged into engagement with the web of the bar, a longitudinally extending cam trip mounted thereon and extending radially therefrom, a lever mounted upon the column and having one end engageable by said trip as the shaft rotates and the other end engaging with the bolt, a movement of the cam trip against said lever causing the retraction of the bolt from engagement with the bar, a gear wheel mounted upon the crank shaft, a gear wheel loosely mounted upon the longitudinal shaft and having a clutch member, a clutch member slidably mounted upon the shaft but rotating therewith and coacting with the first named clutch member and resiliently urged toward the latter, and means for retracting the second named clutch member from the first named clutch member when the carriage reaches either end of its travel at the opposite ends of the pipes, the cam shaft having a rotation approximately one-half the speed of rotation of the crank shaft and each clutch face having clutch teeth disposed in quartering relation.
- 20 15. The combination with parallel steam pipes, and overhead transversely extending beams having hangers supporting the steam pipes, of means for cleaning the pipes comprising a longitudinally extending T-shaped rack bar mounted in guides operatively supported upon said beams, the depending web of the bar being provided with notches at intervals, a power driven crank shaft having a crank operatively connected to the bar to constantly reciprocate the bar, a carriage extending beneath the series of pipes, a plurality of pipe brushes mounted upon said carriage, each for engagement with a pipe, a column extending upward from the carriage and having a slot receiving the depending web of the bar, a bolt mounted within the column and resiliently urged into engagement with the web of the bar, a longitudinally extending shaft having a longitudinally extending cam trip mounted thereon and extending radially therefrom, a lever mounted upon the column and having one end engageable by said trip as the shaft rotates and the other end engaging with the bolt, a movement of the cam trip
- 25 30 35 40 45 50 55 60 65 70 75 80 85 90 95 100 105 110 115 120 125 130

- against said lever causing the retraction of the bolt from engagement with the bar, a gear wheel mounted upon the crank shaft, a gear wheel loosely mounted upon the longitudinal shaft and having a clutch member, a clutch member slidably mounted upon the shaft but rotating therewith and coacting with the first named clutch member and resiliently urged toward the latter, and means for re-
 5 tracting the second named clutch member from the first named clutch member when the carriage reaches either end of its travel at the opposite ends of the pipes, the cam shaft having a rotation approximately one-half the speed of rotation of the crank shaft and each clutch face having clutch teeth disposed in quarreling relation, said retracting means including levers supported in the path of travel of said column, and a connecting rod engag-
 10 15 20
 25 30
16. In a pipe cleaning apparatus of the character described, the combination with a pipe and a member traveling beneath the pipe, of columns extending upward from said member, there being a pair of columns on each side of the pipe, each pair of columns being joined by a bolt, semi-circular brush backs having radially projecting bristles engaging the pipe and having vertically extending shanks, each shank having a hook engaging said bolt, and bolts engaging the upper end of each shank with the corresponding pairs of columns.

17. In an apparatus of the character de-
 scribed, a plurality of parallel pipes, a trans-
 versely extending carriage extending beneath
 the pipes and extending upward at their outer
 ends and having supporting wheels, a plu-
 rality of sets of brushes mounted upon the car-
 riage and each including approximately arcu-
 ate backs having bristles extending inward
 and toward the corresponding pipe, and power
 operated means for reciprocating the carriage
 and simultaneously causing the carriage to
 travel from one end of the pipes to the other
 and back again.

18. In an apparatus of the character de-
 scribed, a pipe, supports disposed above the
 pipe, hangers for the pipe, each hanger en-
 gaged with said supports and each hanger
 including a relatively thin, depending, metal-
 lic member, a relatively thin pipe-embracing
 portion attached to said member and embrac-
 ing the grainer pipe, brushes disposed
 upon each side of the pipe and each including
 a semi-circular member having inwardly pro-
 jecting bristles contacting with the pipe, ver-
 tical, resilient, supporting members to which
 the semi-circular members are attached, sup-
 ports for said resilient members, and means
 for shifting said last named supports lon-
 gitudinally of the pipe to thereby clean the
 pipe.

In testimony whereof I hereunto affix my signature.

THORVALD C. COLBIORNSEN.
